TO AUTOMATIC SPRINKLER COMPANY OF AMERICA, OF CLEVELAND, OHIO, A COR-
PORATION OF DELAWARE

SUPERVISING THERMAL SYSTEM

Application filed July 20, 1927. Serial No. 207,098.

Our invention relates to that type of fire detecting apparatus in which increase of air pressure in the pipe is employed to control the action of mechanism whereby a fire extinguishing medium may be supplied through a pipe or outlet for the purpose of extinguishing the fire or whereby a door or barrier may be opened or closed or a signal given or other useful work performed in connection with the control of the fire.

Our invention relates more particularly to means for supervising such system so that should it become impaired, as for instance through the accidental puncture, rupture or wilful removal or breakage of the piping through which the increase of air pressure is conveyed, a signal or indication, visible or audible, will be given.

The invention relates particularly to a system in which the tube for conveyance of the air pressure to the central point is a supplemental air tube and is connected in the fire area or zone preferably with air containers or bulbs wherein the air being heated and expanded by the fire or increase of temperature in the fire zone operates through said tube upon the signal indicating or valve controlling apparatus at the central point or points of supervision.

While we have described our invention in connection with the use of the air bulb or container for producing directly an increase of pressure in the air tube, it will be understood from the subjoined description that other means thermostatically controlled or operated might be employed for producing increase of pressure in said tube, as for instance in the manner described in the prior application for patent of E. A. Lowe, filed November 11, 1925, Serial No. 68,283, wherein a spring or other source of stored power adapted to actuate a bellows arrangement connected with the tubing is employed, and said bellows arrangement acts as the means for producing the increase of pressure when released for action through the influence or control of a thermostat responsive to increase of heat in the fire zone or area to be protected.

Our invention consists essentially in main-

taining in said air tubing a normal pressure or plenum of air which will permit the transmission of the actuating impulse for the controlled mechanism but which also, on fracture or sudden leak in the tube, will bring about a decrease of pressure upon a pressure responsive device whose response to the decrease of pressure is made effective through suitable apparatus for giving a signal indicating the presence of a break or defect in said tubing.

Our invention consists further in the special combinations of apparatus hereinafter more particularly described and then specified in the claims.

In the accompanying drawings Fig. 1 shows in general diagrammatic fashion and in partial vertical section apparatus embodying our invention.

Fig. 2 is a perspective view of a detail. 70

3 indicates the air tubing through which an increased pressure of air is conveyed for the purpose of controlling any suitable mechanism as will be hereinafter more particularly described. According to our present invention said tubing contains air normally maintained under pressure above that of the normal atmospheric pressure and the means for producing the increased pressure therein by thermostatic action comprises in 80 the preferred form of our invention bulbs or heat detecting units 2 of any desired number, preferably of metal, and containing comparatively large bodies of air adapted to respond to increase of temperature in the atmosphere surrounding said bulbs or units. These bulbs or units are in communication with the pipe 3 so that, as will be obvious, a heating of one of them will produce increase 85 of pressure in the piping 3 which increase of pressure is conveyed to the devices to be presently described embodying as an essential part of them a means responsive to increase of air pressure such as a diaphragm 5. The containers 2 are preferably placed near 90 the ceiling of a room or enclosure to which the system is applied so that they will be more quickly affected by any abnormal increase of heat therein.

4 indicates a diaphragm case or chamber 100

connected with the piping 3 and 5 a flexible wall or diaphragm that in the present embodiment of the invention is clamped tightly between flanges on the case 4 and chamber 5 4' below the diaphragm. A bypass 6 connects the piping 3 with a space below the diaphragm 5 as indicated and has in it a restricted section or passageway 7. Should any increases of the normal pressure in 3 be at a gradual or slow rate, and due for instance to changes of atmospheric temperature, the restricted section 7 will permit the air to gradually leak or pass from 3 to the space beneath the diaphragm 5 and equalization of pressures upon the opposite sides of the diaphragm will thereby be maintained and the diaphragm will remain at rest. Should however there be a sudden increase of pressure in 3, as for instance an increase due to the thermostatic action of a container 2, the restricted section 7 will be inadequate to allow the accumulated pressure above the diaphragm to pass to the space below the diaphragm and become equalized thereon and as a result the diaphragm 5 or other pressure responsive device will be forced downwardly and, through devices to be presently described, will bring about the action of any suitable controlling mechanism for establishing a supply of fire extinguishing medium which may pass to the main distributing piping the beginning of which is indicated at 30, or may bring about the operation of other devices useful in controlling the fire.

Should sudden break or rupture of the piping 3 occur, allowing a sudden decrease of the pressure maintained therein, the equalization of the pressures in the chamber with which piping 3 is connected directly and in the chamber 4' indirectly connected therewith through the restricted bypass will be destroyed and any pressure responsive device, as for instance the diaphragm 5, subjected to the opposing pressures will be caused to move or respond and this responsive movement we utilize in the controlling action of a suitable signalling or indicating device whereby the abnormal condition of the apparatus will be indicated, so that the same may be quickly repaired and the device restored to working condition immediately.

To convey or translate a movement of the pressure responsive device like diaphragm 5 to the mechanism whose controlling action is subject to the varying pressures we may employ the following devices.

9 is an arm in chamber 4' which passes through any suitable air-tight joint indicated at 19 and comprising, for instance, a flexible diaphragm to which the arm is attached, said diaphragm itself being clamped against a wall of the casing 4, as shown, by means of a threaded clamping member 20. Motion may be communicated from the diaphragm to the arm 9 through a suitable flexible member 10.

Obviously lever 9, being secured to the flexible diaphragm 19, may oscillate upward or downward through the action of the pressure responsive device 5.

The air pressure required in the piping 3 may be supplied and maintained by devices similar to those described in our prior application for patent filed January 26, 1927, Serial No. 168,629, and comprising the following parts, or by other means.

26 is a pump which may be a hand pump adapted to force air through a check valve 25 and a globe valve 24 which may be opened when the air pressure is to be replenished and through pipe 27 into a chamber 14. Connected with this chamber or forming a wall thereof is a flexible diaphragm 12 which will be forced to the left by the increase of pressure in 14 due to the action of the pump. A spindle or rod 13 carried by said diaphragm has a notched end that, by the movement of the diaphragm under increase of pressure in 14, will be carried over the end of lever 19 thus preventing the latter from either rising or falling during the process of pumping and replenishing the air. At the same time with the movement of the rod 13 which thus locks the lever 9, a collar 28 on a rod or extension on the inside of the diaphragm 12 and working in chamber 14 acts upon the bell crank lever 14' and lifts the valve 15 connected with said bell crank lever from its seat, thus permitting the air forced into the chamber 14 by the pump to enter first the chamber 4' from which it escapes through the equalizing vent 7 into the system of tubing 3 thereby finally restoring the pressure in the piping 3, at the same time permitting the pressure on the opposite sides of the diaphragm 5 to be finally equalized.

Movement of the rod 13 under the action of diaphragm 12 also carries projecting arms 29 and 29' to the left past lugs 18, 18' on the yoke 11, attached to the diaphragm 5 so that while the diaphragm 5 is in lifted position under the influence of the pressure in 4' and until the pressure becomes equalized on opposite sides, the rod 13 will be prevented from receding from its position for locking lever 9. When however the pressure has become equalized the diaphragm 5 will resume the position shown in the drawings and the rod 13 will therefore be released and permitted to return to the normal position by the operation of the diaphragm 12 due to pressure of the air in the chamber 4' thus leaving the lever 9 in condition to respond to an increase of the established pressure in 3 or to a sudden decrease thereof in case of breakage of the piping 3.

When our invention is applied to the control of mechanism for supplying fire extinguishing fluid to distributing piping such as devices such as now to be described may be employed.

31 and 32 respectively indicate the two members of a differential valve or valve working by bypass pressure applied to the back of member 31 through a passage 33 connecting with a source of fire extinguishing fluid supply 34 the passage of which into piping 30 is controlled by member 32 normally seated by the pressure of the bypass fluid acting on the greater area of 31. The relief of the bypass pressure through another and larger opening permits member 32 to be lifted by the pressure in 34 thus establishing connection between 34 and 30. Such relief of pressure may be effected by means of valve 35 carried by rod 36 and controlling the escape of the fluid back of member 35 to an escape pipe 37. Valve rod 36 is normally held in lifted position, if desired by the spring action of a collapsible bellows-like member 18, preferably 20 of metal, normally held distended or extended by its own resiliency assisted, if desired, by a spring. Said member is in the form of a chamber and has the outer end of said valve stem 36 attached or connected to 25 it near its upper end. The lower end of said member or chamber surrounds the valve stem where it extends from the valve body and is sealed at such point thereby avoiding leakage and making it unnecessary to employ the 30 usual packing for the stem which would interfere with the free movement thereof. The upper end of the collapsible chamber 38 is adapted to be engaged by a weighted arm 39 carrying weight 22 and normally restrained 35 or held in lifted position by a detent or catch engaged by the end of the extension 21 from rod 9. A movement of said extension 21 upward obviously will free the arm 39 which will descend under the action of the weight 40 and open the valve 35.

The mechanism controlled by the action of the arm 9 might also include or comprise, if desired, means for giving a signal or alarm or other indication, for which purpose we 45 may employ an electric circuit closer 40 adapted to be engaged by an arm extending from lever 39 when the latter drops and to close the circuit of a bell or indicator 41 thereby giving an audible indication of the fact 50 that the apparatus has responded to increase of pressure above the normally maintained pressure in the piping 3. The means for indicating a sudden or abnormal drop of pressure in 3 beyond the normally maintained 55 pressure may comprise the bell or indicator 41 controlled in its action through a lifting of the diaphragm 5 by means of the detent or catch on the outer end of lever 9 which is adapted, as shown, (see Fig. 2) to release 60 arm 39 when the outer end 21 is depressed through lifting of the end within the casting 4.

The operation of the apparatus will be as follows:

65 Positive pressure of air subsisting in pip-

ing 3 will increase if the thermostatic members 2 or either of them are exposed to abnormal or sudden increase of heat. Such increased pressure will produce upon the upper side of pressure responsive diaphragm 5 70 pressure superior to that below the same since the bypass opening 7 will not allow air to pass at a sufficiently rapid rate to maintain the normal equalizations of pressures at the opposite sides of diaphragm 5. As a consequence the diaphragm 5 being depressed, will depress the inner end of lever 9 and lift the outer end 21, thus freeing the controlling mechanism. The weighted lever 39 will drop and open the valve 35 whereupon the valve 32 controlling the supply of fire extinguishing medium will open in obvious manner and with obvious result. Should a sudden decrease of pressure in the piping 3 occur through mechanical injury thereto the 80 pressure in chamber 4 above the diaphragm 5 will suddenly decrease and said diaphragm will be lifted owing to the fact that there will be beneath the same a superior pressure. Said diaphragm thus responding to the decrease of pressure in 3 will lift the inner end of lever 9 thus depressing its outer end and releasing the weighted lever 39 which will thereupon cause the circuit of the bell or indicator 41 to be closed and a signal or indication of the breakage or abnormal condition 85 of piping 3 indicated.

In the improved system shown and described it will be obvious that the condition of pressures, whether of air or liquid, in the 100 piping 30, is immaterial and that by employing increased pressures of air in a supplemental piping in which pressure is normally maintained and by the use of proper signalling or indicating devices we can not only 105 supervise or keep under control readily the condition of air pressure in said supplemental piping but secure the further advantage that the maintenance of a pressure of air or other fluid in the piping 30 is unnecessary and 110 that we avoid the difficulties due to the greater liability of leaks or disturbances in those cases where the variations of air pressure in the distributing piping are employed in connection with the mechanism for establishing 115 automatically a supply of the fire extinguishing medium thereto.

What we claim as our invention is:

1. In an apparatus of the character described, the combination of air tubing and 120 air bulbs or containers connected therewith and containing air under pressure, said bulbs or containers being placed in fire zones and subjected to the heat condition thereof for affecting the pressure in said tubing, of a 125 weighted actuating device normally held out of action and means for releasing the same by either a sudden increase or decrease of the air pressure in said tubing.

2. In an apparatus of the character de- 130

scribed, a supplemental system of air tubing containing air maintained at pressure greater than atmospheric pressure and provided with means in a fire zone for increasing said pressure in response to an increase of temperature in said zone, valve controlling apparatus responsive to a sudden increase of said normal pressure due to actuation of said pressure varying means in the fire zone and signalling means responsive to a sudden decrease of the normal pressure in said tubing due to break or leak in said air tubing.

3. In a fire extinguishing apparatus, the combination with means controlling the supply of fire extinguishing medium, supplemental air piping containing air under pressure and provided with means in a fire zone for increasing said pressure in response to an increase of temperature in said zone, means responsive to a sudden increase of pressure in said piping for bringing said controlling means into action and means responsive to a sudden decrease of the pressure in said tubing upon breakage or interruption thereof for operating a signal for indicating such abnormal condition.

4. In a fire extinguishing apparatus, the combination of a valve controlling the supply of fire extinguishing medium, a supplemental piping containing air under pressure and provided with means in a fire zone for varying the pressure therein, a pressure responsive device responsive to a sudden variation of said normal pressure, means controlling the action of said valve and adapted to cause the same to open in response to the action of the pressure responsive device when the pressure increases in said piping and means controlled by said pressure responsive device for automatically indicating a decrease of the normal pressure in said piping.

5. In an apparatus of the character described, the combination with a main valve and its control means controlling the admission of fire extinguishing medium to a system of piping, a supplemental air tubing containing air normally under pressure and leading from the fire zone to said control means, said tubing including means in the fire zone for increasing the pressure therein, a device responsive to either increase or decrease of pressure in said supplemental piping due respectively to thermal action or to presence of a leak in the piping and means controlled by said pressure responsive device for actuating the control means to cause the main valve to open whenever there is an increase of pressure in said tubing and for giving a signal or indication on variation of pressure therein due to breakage or leak in the tubing.

6. In a system of the character described, the combination with a main valve controlling the admission of fire extinguishing me-

dium to the main piping, a supplemental system of air piping containing air under pressure and terminating in a chamber closed by a pressure responsive diaphragm, said system of air piping extending to a fire zone and including devices for increasing the pressure therein responsive to an increase of temperature in said zone, a restricted bypass from said tubing to a space at the opposite side of said diaphragm for balancing the effect of the normally maintained pressure in said piping upon the diaphragm, means controlled by said diaphragm when it responds to sudden increase of pressure in the piping for causing the main valve to open and means for giving a signal or indication of the movement of said diaphragm in the opposite direction due to sudden decrease of normal pressure in said supplemental piping.

Signed at Cleveland in the county of Cuyahoga and State of Ohio this 12 day of July A. D. 1927.
